DISPENSING MEANS

Abraham M. Malouf, Los Angeles, Calif.

Application December 2, 1938, Serial No. 243,538

7 Claims. (Cl. 221—14)

This invention relates to dispensing means and more particularly to a novel form of nozzle or spout which may detachably engage some container whereby liquids and granulated solids may be readily dispensed from said container.

An object of the present invention is the provision of a dispensing nozzle or spout which will permit the dispensing of substances rapidly and which dispensing may be readily stopped at the will of the operator. In the case of liquids, the device so functions that there is no drip from the nozzle or spout when flow of liquid therethrough is shut off.

The invention contemplates a novel method of allowing air to enter any container upon which said nozzle or spout is mounted so as to assure steady flow of a liquid or other substance through said nozzle or spout. The invention is adapted for readily permitting the dispensing of viscous liquids, and to this end, the device of the invention is so constructed as to at all times maintain the air opening clean of said liquid.

Other objects include an invention which is simple in construction, easily applied to a container, and inexpensive in cost of manufacture.

With the above mentioned and other objects in view, the invention consists in the novel and useful provision, formation, construction, association, and relative arrangement of parts, members and features, all as shown in certain embodiments in the accompanying drawing, described generally, and more particularly pointed out in the claims.

In the drawing:

Figure 1 is a side elevation of a bottle, the neck of which carries one form of improved dispensing nozzle or spout.

Figure 2 is a sectional view on the line 2—2 of Figures 1 and 3.

Figure 3 is a vertical sectional view of the invention shown in Figures 1 and 2.

Figure 4 shows a modified form of the invention as applied to a container having a screw neck.

Figure 5 is a view taken 90 degrees from the showing of Figure 4.

Figure 6 is a sectional view on the line 6—6 of Figure 5.

Figure 7 is a sectional view on the line 7—7 of Figure 6.

Figure 8 is a longitudinal sectional view of a modified form of the invention shown by Figures 1 to 3, inclusive, and,

Figure 9 is a view looking in the direction of the arrow 9 of Figure 8.

Referring now to that type of the invention shown in Figures 1 to 3, inclusive, the invention is designated as an entirety by the numeral 1 and the same is shown attached to a bottle 2.

5. Referring to Figure 3, the invention 1 includes a body portion or nozzle 3 which has a tapered outer surface 4 for a portion of its length. The body is reduced at 5, and the reduced portion as well as the body is formed with a through bore 6 forming a duct or passage way. The axis of the bore or duct 6 is eccentric to the axis of the body portion 3. In transverse section the body 3 is substantially heart or pear-shaped, see Figure 2, and what would be the neck of the pear is cut away segmentally, as shown at 9, it being observed that the length of the body to said cut 9 is less than the length of the bottom portion of the body, see Figure 3. Conforming to the shape of the body and provided with a bore is a disc 10, the tube 5 being passed through the opening thereof, so that a portion of said disc will bear against the end 11 of the body. This construction permits some element to be positioned between a face of the disc and the face 12 of the body. The body and the disc may be provided with one or more aligned openings, the opening in the body being screw-threaded whereby a screw or similar means, such as indicated by dotted lines at 13, may hold said disc to said body.
10. 20. 25. 30. 35. 40. 45. 50. The body is provided with two concentric bores of different diameter, as indicated at 14 and 15, and the disc is provided with a bore 16 in axial alignment with said bores 14 and 15. Adapted to extend through the bores 14, 15, and 16 is a stem, shaft or trunnion 17, to which is secured a valve 18 of the disc type. The disc is held to the stem or trunnion in any approved manner, such as by passing a pin 19 through aligned openings therein. Within the bore 14 and wrapped around the stem or trunnion is a coil spring 20. One end of said spring bears against the ledge or shoulder 21 formed by the different diameter bores 14 and 15 while the opposite end of the spring bears against a pin 22 transversely passed through the said stem or trunnion whereby the valve is always urged tightly against what may be termed the forward end surface or seat 22a of the body or nozzle.
- At 23 is a second spring, one end of which is secured about the pin 22 and the opposite end of which is received within the cut away portion 9 with a portion of said spring extending outwardly and into a small kerf, as indicated at 24 (see Figure 2).
- 25 is an actuator for the stem or trunnion in

the form of a handle or lever, this lever including an elongated part formed at one end with a finger piece 26. The lever has a bent end extremity 27 provided with a bore through which said stem or trunnion is passed, as shown in Figure 3 and the said stem or trunnion is fastened to said end 27 by pinning or otherwise, as indicated at 28. The lever has a flat head portion 29, which engages the shoulder 30 formed by the transverse cut 9, and likewise a curved portion 31. Thus, when the lever is in the position shown in Figure 2, the valve disc covers the end of the body and closes the opening therethrough. When the finger, such as shown in Figure 1 at 32 moves the lever or handle in the direction indicated by the arrow of Figure 2, the valve disc is moved clockwise to uncover the bore 6 so that any content within the bottle 2 may be poured outwardly of the said bore. Surrounding the part 5 is some means, such as cork, rubber, or the like 33, so that the device may fit tightly within the neck of the bottle 2.

Referring now to the form of the invention shown in Figures 4 to 7, inclusive, Figure 6 illustrates the mechanical parts wherein 50 is a cap internally provided with screw-threads 51, whereby the said cap may be threaded to the neck of a container, such as a jar containing mayonnaise, granulated sugar, or other substances. The cap above the screw-threaded area has an enlarged chamber 52 and an outlet port 53 communicates between the chamber 52 and the outer surface of the cap. The top of the cap carries a diametrical enlargement 54, which enlargement is provided with concentric bores of different diameter, as illustrated at 55, 56 and 57. Passed through said bores is a stem or trunnion 58 carrying at one end a valve 59 in the form of a disc, the disc being pinned to the stem, as shown at 60. This disc when in one position, closes egress through said outlet port, and in a second position allows egress therethrough.

The coil spring 61 within the bore 56 surrounds the stem or trunnion and bears against a shoulder 62 for one end of the spring while the opposite end of the spring engages a pin 63 passed transversely through the stem or trunnion. This said spring urges the stem to the right, viewing Figure 6. The end 64 of the stem is reduced in diameter and carried on said reduced diameter portion and pinned thereto is a lever 65. This lever is substantially of flat stock given a structural twist to provide a finger portion at 66 and a base portion 67, the edge of the base being substantially straight at 68 and then gradually curved, as shown at 69. The flat portion carries a transverse pin 70 received within the confines of an arcuate slot 71 formed in the cap. This arcuate slot communicates with the chamber 52. It is to be observed that the foot of the lever is enlarged in width so that when the lever is in the position shown in Figures 5 and 7 the pin 70 is adjacent the right hand end of the arcuate slot 71 with the said head end of the lever closing the slot 71 throughout its length. When the lever 65 is compressed in the direction of the arrow of Figure 5, the pin 70 travels within the slot 71 and a portion of the lever uncovers said slot so that air may enter the chamber 52. In order to manipulate any container, such as shown at 12, I have provided a handle 73 secured to the cap. This handle may assume any form, such as the curved form illustrated in Figure 4, the handle having a portion adapted to be secured by screw 74 to the

cap, and one end 75 of said handle is enlarged and recessed or chambered, as shown at 76. Within this recess and secured to the enlargement are a pair of flat prongs or pins 77. The end of the enlargement is adjacent the foot of the lever 65. A coil spring 78 has one end received between the prongs 77 and the opposite end passed through a transverse opening in the foot of the lever, as shown at 79.

10 Figure 8 illustrates a modified form of the invention shown in Figures 1 to 3, wherein I have provided in combination with the device means whereby a measured quantity of liquid may be dispensed. The device as shown includes a body 15 formed in two parts 100 and 101, which may be secured together through the medium of screws 102 received in tapped openings in the body part 100. The body parts are both provided with coaxial longitudinal bores 103 and 104, within 20 which liquid may be received and likewise dispensed therefrom. The forward end of the body part 100 has positioned thereon a disc valve 105. This disc valve has eccentrically secured thereto by pinning or otherwise a shaft 106, which shaft 25 is within bore 107. Within the bore 107 are two coil springs 108 and 109, both of which surround the shaft. The spring 108 is attached to the shaft and bears against an end wall of the body part so as to normally urge the shaft inwardly 30 and thereby press the disc valve 105 tightly against the end of the body 100. In effect, a ground-fit engagement occurs between the disc valve and said end to prevent any liquid from escaping past the valve when the valve is closed 35 over the opening 103. The spring 109 functions to normally maintain the valve closed and to resist turning movement of the shaft. The body part 101 is provided with a bore 110 coaxial with the bore 107. Within this bore is a shaft 111 in 40 axial alignment with the shaft 106. One end of said shaft carries a disc valve 112 which may be swung to position the same over the opening 104 (see Figure 9). Surrounding the shaft 111 is a coil spring 113, this spring having one end 45 fixed to the said shaft, whereby the disc valve is urged into tight engagement with its valve seat. The inner ends of both shafts 106 and 111 are externally squared, as shown at 114, 115 and the body 100 is cut away in such a manner that a lever 116 may be received between both body parts 100 and 101 and positioned on the squared portions of the shafts. In this manner, the single spring 109 acts to resist turning of both 50 shafts when the handle is moved. The relationship of the disc valves is such that when one valve is opened the other is closed. The body part 101 has a reduced diameter portion upon which is received an annular cork whereby the instrumentality as a whole may be positioned within the 55 neck of a bottle or similar object.

The operation, uses and advantages of the invention just described are as follows:

First, referring to the form of the invention illustrated in Figures 1 to 3, and assuming that the device is secured in the neck of a bottle, as shown in Figure 1, movement of the lever in one direction by the finger 32 engaging the finger piece 26, will tend to tighten the spring 23 which normally holds the valve disc positioned over the end of the body. Movement of the lever against the spring will unseat the disc and thus permit any liquid within the bottle to pass through the bore 6 and outwardly thereof. The moment the handle is released, the spring 23 will rotate the valve disc to a closed position and

cut off any flow of liquid through the bore 6. The spring 20 always holds the valve disc tightly against its seat. By way of illustration, it may be said that the spring 20 is normally under a tension of approximately five pounds. Thus, as there is a ground fit engagement between the valve disc and its seat, the valve when closed is fluid tight.

The form of the invention illustrated in Figures 4 to 7 operates on the same principle as the device just described in that it has a spring for normally urging the disc valve into seated position and a spring for returning the valve over the outlet port when the handle is released. However, as the form of the invention illustrated is adapted to handle viscous liquids, such as syrups, mayonnaise, and the like, such substances may clog the air inlet opening 71 and to overcome this, the pin 70 moves within the slot 71 to clear said air opening each time the handle is actuated.

The operation of the form of the invention illustrated in Figures 8 and 9, is as follows: Normally the operator, with the device of Figure 8 positioned within the neck of a bottle, will tip the bottle so that the liquid within the bottle may be received within the bores 103 and 104. We will say that the bores will hold the equivalent of one jigger. When the handle 116 is moved, the valve 112 will be closed over the opening 104 and the valve 105 opened. Thus, one jigger of liquid is dispensed. Upon releasing the lever, the operation is repeated.

I claim:

1. In a device of the character disclosed, a housing formed with a bore through which a substance may pass, a disc valve for closing one end of said bore, a trunnion secured to said disc and chambered within said housing out of communication with said bore, means for urging said disc into liquid tight seated engagement with an end of said housing, spring means for normally maintaining said disc closed over said bore, and a handle for rotating said trunnion against said last named means for swinging said disc to one side of said bore.

2. In a device of the character disclosed, a dispensing nozzle including an enlarged portion and a tubular portion, the enlarged portion having a bore communicating with the tubular portion, said tubular portion adapted to be received within the neck of a container, means for sealing said tubular portion liquid-tight within said neck of said container, a swing valve normally closing the bore through said enlarged portion, means for urging said valve into tight engagement with an end of said enlarged portion, and means urging said valve at all times to cover said bore.

3. In a device of the character disclosed, a cover, for attachment to a container, an outlet port in said cover, a swing valve normally closing said outlet port, a trunnion secured to said swing valve, and a handle for rotating said trunnion for moving said valve, means resiliently urging said valve into seated position against said cover, means normally rotating said trunnion to maintain said valve seated, and said handle having a part adapted to cooperate with said cover to limit rotation of said trunnion in one direction to position the valve over said outlet port.

4. In a device of the character disclosed, a dispensing nozzle provided with a bore through which liquid may be passed, and a pair of

valves adapted to alternately open and close opposite ends of said bore, whereby a measured quantity of liquid may be dispensed through said nozzle, and a spring for normally maintaining each of said valves, when closed, in liquid-tight engagement with its seat.

5. In a device of the character as disclosed, a housing formed with a bore, through which a liquid may pass, and with a trunnion bore, a trunnion extending through said trunnion bore and slidably and rotatably mounted in said housing, a valve on the outer end of said trunnion, a coil spring surrounding said trunnion for holding said valve in liquid-tight engagement with the outer end of said housing over the outer end of said bore, when said valve is in closed position, a handle for turning said trunnion and opening said valve, and a coil spring surrounding said trunnion for turning said trunnion and closing said valve over the outer end of said bore when said handle is released.

6. A device of the character disclosed, including a dispensing nozzle comprising a body portion formed with a rearwardly extending tubular portion and with a dispensing bore forming a continuation of the interior of said tubular portion and extending through the forward end of said body, a cork fitted on said tubular portion for fitting the interior of the neck of a bottle, a trunnion journaled and enclosed within said nozzle out of communication with said dispensing bore, a swing valve on the forward end of said trunnion, a spring coiled around said trunnion for normally holding said swing valve in position closing the forward end of said dispensing bore, a second spring coiled around said trunnion for holding said swing valve under tension against its seat in closed position over the forward end of said dispensing bore, and a handle connected to said trunnion for swinging said valve open for dispensing liquid from said bottle through said tubular portion and said dispensing bore.

7. A device of the character as disclosed including a dispensing nozzle comprising a body formed with a rearwardly-extending portion, said nozzle being formed with a dispensing bore extending through said body and said rearwardly-extending portion, a cork fitted on said rearwardly-extending portion for fitting the interior of the neck of a bottle liquid-tight, a pair of valve shafts journaled and enclosed within said nozzle out of communication with said dispensing bore, an operating handle, said nozzle being slotted to receive the inner end of said handle, said inner end of said handle being provided with a flat-sided opening, one end of each of said valve shafts being flat-sided and fitted in said flat-sided opening in said end of said handle, a swing valve on the outer end of one of said shafts, a swing valve on the inner end of said other shaft, a spring coiled around one of said shafts for normally holding said shafts in position with one of said valves closing the outer end of said dispensing bore and said other valve closing the inner end of said bore, other springs coiled around said shafts, respectively, for holding said valves in liquid-tight engagement with their seats while closing the outer end and the inner end, respectively, of said dispensing bore.

ABRAHAM M. MALOUF.
